UNITED STATES PATENT OFFICE

2,521,445

FLOOR MOP HAVING A WRINGING MECHANISM MOUNTED THEREON

Larkin H. Brown, Los Angeles, Calif.

Application February 14, 1946, Serial No. 647,443

2 Claims. (Cl. 15—119)

1

This invention relates to mops and the principal object of the invention is to provide a mop having simple and efficient means for wringing the water out of the mop cloth or water absorbent mopping member which is connected therewith.

Another object of the invention is to provide a self-wringing roller sanitary mop which is easy to operate, sanitary in use and especially adapted for use in hospitals though it could be as successfully used in homes and other places.

A further object of the invention is to provide a mop that is simple in construction, efficient in operation, durable and reliable in use and economical to manufacture.

With the above and other objects in view, the invention consists of the novel details of construction, arrangement and combination of parts more fully hereinafter described, claimed and illustrated in the accompanying drawings in which:

Figure 1 is a longitudinal sectional view of an embodiment of the invention;

Figure 2 is a side elevational view thereof on the line 2—2 of Figure 3;

Figure 3 is a plan view on the line 3—3 of Figure 1;

Figure 4 is a plan view with the cover removed;

Figure 5 is an end view with the mop and handle removed and as viewed on the line 5—5 of Figure 2;

Figure 6 is a fragmentary and sectional view of the connection of the chains with the handle;

Figure 7 is a sectional view on the line 7—7 of Figure 4.

Referring more in detail to the drawings the reference numeral 10 comprises the channel shaped housing having an upturned end 13 to which a channelled shaped cover 12 is hingedly connected by means of a hinge 11, to provide a unit assembly substantially triangular in cross section.

A bracket 14 secured to the bottom of the housing 10 by fasteners 16 mounts a shaft 18 to which there are secured rollers 20 for movement of the housing over the surface to be cleaned.

Bearings 22 secured to the front of the housing 10 on opposite sides thereof by fasteners 24 are adapted to mount a shaft 26 therein which extends transversely of the housing and is provided with sprockets 28 adjacent the ends thereof and mounted on the shaft 26 intermediate of the sprockets 28 is the roller 30.

Secured to the rear of the housing 10 by means of fasteners 32 are bearings 34 which are adapted

to mount a shaft 36 on which are mounted the sprockets 38, which are connected to sprockets 28 by the sprocket chains 40.

Mounted at the forward edge of the cover 12 for contact relation with the roller 30 is a second roller 42 mounted on a shaft 44 parallel to the shaft 26 and moveably mounted in the opened ended slots 46 in the sides of the cover 12 by means of floating bearings 47 and also mounted on the shaft 44 are the sprockets 48 which are in parallel relation with the sprockets 28 on the shaft 26.

Secured to the rear of the housing 10 in parallel relation to the bearings 34 by means of fasteners 50 are the bearings 52 which are adapted to mount a shaft 54 in parallel relation to shaft 36 on which are mounted the sprockets 56 parallel to the sprockets 38 and the former are connected to sprockets 48 by sprocket chains 58 in parallel relation with the chains 40.

The ends of the chains 40 and 58 are connected to a plate 60 at the center of which is mounted a rod 62 which extends transversely of the housing 10 and passes through the longitudinally extending handle 64 and the rod 62 is retained in position by cotter pins 66.

Mounted in the upturned end 13 of the housing 10 is a guide tube 68 having a circular flange 70 which is secured to the housing 10 by the fasteners 72 and the handle 64 is slidably mounted therein.

The forward end of the handle 64 is provided with head coupling 74 to which the mop material 76 is fastened, and the coupling 74 is secured to the handle 64 by fasteners 78.

Mounted at the forward end of the housing 10 is a mop material shield 80.

The cover 12 is provided with an alinement lip 82 adapted to seat in the recess 84 in the housing 10. Elongated guideways 86 are provided in the sides of the cover and housing to permit free reciprocation of the rod 62. The half moon spring clips 88 mounted in eyes 90, secured to the housing and cover, tension the rollers against the mop material for the wringing thereof.

In operation the mop material is pushed outwardly of the housing by pushing on the handle 64. The mop is saturated with the cleaning liquid and by applying the mop to the floor and engaging the floor with the roller 20 the entire assembly may be pushed over the floor for the mopping thereof. When it is desired to wring the mop the mop material is drawn through the rollers for the extraction of water thereof by pulling the handle 64 so that the mop material is

drawn between the rollers 30 and 42. Thus a device is provided which will quickly and expeditiously extract water from the mop material without the necessity of wringing the mop by hand.

It is thought that persons skilled in the art to which the invention relates will be able to obtain a clear understanding of the invention after considering the description in connection with the drawings. Therefore, a more lengthy description of the operation thereof is regarded as unnecessary.

It is also to be understood that changes in the details of construction, arrangement and combination of parts may be resorted to within the spirit of the invention and the scope of the appended claims.

Having thus described the invention what is claimed as new and desired to be secured by Letters Patent is:

1. A self-wringing mop comprising a housing of channel shape having an upturned end with a sleeve guide therein, a cover hinged to the upturned end of the channel, rollers respectively extended across the ends of the housing and the cover opposite the upturned end, a mop handle slidable through the guide sleeve and having a head thereon with mop material attached to it and adapted to be drawn between the rollers, shafts journaled in the sides adjacent the upturned end of the housing, said rollers having sprockets and said last mentioned shafts having sprockets, these sprockets being disposed at opposed sides of the rollers and of the shafts, chain devices extending between the sprockets, means for connecting the chain device to the handle whereby to cause the chain device to be

operated as the handle is drawn through the guide sleeve and the mop material through the rollers, and biasing means for maintaining the rollers together and the cover closed upon the housing.

2. A self-wringing mop as defined in claim 1, wherein said means for connecting the handle to the chain device comprise plates interconnecting the chain ends, and a shaft connected to and extending between the plates and through the sides of the housing and through the mop handle, said housing having a slot for receiving the shaft whereby to cause the same to be guided as it is moved by the chain device.
